UNITED STATES PATENT OFFICE.

FREDERICK W. BARNES, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINTING MACHINE.

1,266,385.

Specification of Letters Patent. Patented May 14, 1918.

Application filed October 27, 1915. Serial No. 58,277.

To all whom it may concern:

Be it known that I, FREDERICK W. BARNES, of Rochester, in the county of Monroe and State of New York, have invented certain new and useful Improvements in Photographic-Printing Machines; and I do hereby declare the following to be a full, clear, and exact description of the same, reference being had to the accompanying drawings, forming a part of this specification, and to the reference-numerals marked thereon.

My present invention relates to photography and more particularly to apparatus for making photographic prints and it has for its object to provide a simple, cheap and efficient machine of this character with which the amateur can afford to equip himself and which is adapted to be effectively operated by persons of non-professional experience. The improvements are directed more particularly toward the manner in which the lamp or source of artificial light is mounted and may be manipulated to intensify or to lessen its actinic action on a given portion of the superposed negative and sensitive medium and the invention comprehends provision for such adjustments in combination with means for adjusting the area to be exposed whereby the center of the print is not always in the same relative position. To these and other ends the invention resides in certain improvements and combinations of parts all as will be herein-after more fully described, the novel features being pointed out in the claims at the end of the specification.

In the drawings:

Figure 1 is a top plan view of a photographic printing machine constructed in accordance with and illustrating one embodiment of my invention and showing in plan the devices for positioning and holding the negative and print with reference to the printing aperture;

Fig. 2 is a similar view with the top or cover removed;

Fig. 3 is a vertical section taken substantially on the line 3—3 of Fig. 1;

Fig. 4 is a fragmentary transverse section taken substantially on the line 4—4 of Fig. 3;

Fig. 5 is an enlarged transverse fragmentary section taken substantially on the line 5—5 of Fig. 3, and

Fig. 6 is a fragmentary horizontal section taken substantially on the line 6—6 of Fig. 3.

Similar reference numerals throughout the several views indicate the same parts.

In the present embodiment of the invention, a light, portable apparatus is contemplated and electrical illumination is provided. It consists of a substantially light-tight box 1 closed at the top by a preferably detachable cover frame 2 having a printing aperture or opening 3 in which is set a glass table 4. Within the box beneath the aperture are arranged two electric lamps 5 and 6 supplied by wires 7 passing to the exterior. In the present instance, the lamp 5 furnishes the printing light while the lamp 6 has a ruby globe or is otherwise rendered non-actinic and serves as a pilot light to aid in properly positioning the work and in other ways. The ventilating arrangements of the box are shown at 8 and 9.

The cover frame 2 is fitted with a hinged platen 10 that serves, as usual, to hold the print in intimate contact with the negative and to press them both tightly against the table 4. The platen is held down in this operative position by suitable locking arrangements 11 as shown in Fig. 3, which when released permit the platen to be raised and a fresh sheet of print paper laid upon the negative. There are also circuit making and breaking devices, indicated generally at 12, for automatically turning the lamps on and off with the movements of the platen but this subject-matter forms no part of the present invention.

A clamping plate 13 hinged at 14 and disposed along one edge of the aperture 3 serves to grip one edge of the negative and to hold it in fixed position. It is spring pressed into engaging position and released when desired by a rock arm 15 extending beneath it. This plate defines one margin of the printing aperture, an adjacent margin of which is defined by a fixed plate 16. The other two margins are adjustable to accommodate negatives of different sizes and to mask off portions of a large negative, if desired, so that only a portion of its field may comprise the subject of the print. These adjustable margins are constituted by sliding plates 17 and 18 guided on relatively angular rods 20 and 21 and locked in different positions of adjustment by spring catches 22

taking into notches 23 in the rods. The portion 24 of the cover frame 2 is suitably cut away to permit both plates to pass partially beneath it. It will thus be seen that the 5 actual opening through which the light passes may be restricted or enlarged and as its rectangular area is changed, the position of the center of its field changes also.

In order to permit the printing lamp 5 to 10 be positioned directly beneath a negative or printing area of any size or beneath any particular part of the negative so that its action will be intensified at that point, I mount both lamps but especially the lamp 5 upon 15 a movable support so that it may travel back and forth in all directions on the bottom or floor of the box 1 transversely of the printing aperture 3. For this purpose, a track 26 is secured to the box bottom to extend 20 longitudinally thereof and slidable on this track is a carriage 25 having relatively transverse tracks 27 fixed thereto. Slidable in the tracks 27 is a second carriage 28 having fixed thereto a board 29 that forms the 25 mount for the lamp sockets 30. A shaft 31 having an exteriorly arranged operating knob 32 extends through a wall of the box 1 and is journaled in the tracks 27 in such manner that its endwise movement relatively 30 thereto is prevented though it may rotate freely. In the present instance, the journal consists of a bearing strap 33 secured to the track 27 and embracing a reduced portion 34 on the shaft. Beyond the bearing the shaft 35 is provided with a gear 35 that meshes with a rack 36 on carriage 28.

The operation of this lamp support is obvious. By pushing or pulling on the shaft 31, the two carriages remain locked together 40 and through the medium of the lower one 25, the upper one 28 directly supporting the lamps is moved to any desired position longitudinally of the chamber. When the shaft is rotated, the lower carriage 25 remains 45 stationary and, through the medium of the rack and pinion 35-36, the upper carriage 28 is adjusted on the lower carriage to any desired position in a direction transversely of the chamber.

50 The electrical connections 7 are, of course, of a flexible nature permitting the desired range of movement.

It will be seen that the above described

printing machine is very simple in construction and operation and can be produced at 55 low cost and within the reach of the average amateur photographer.

I claim as my invention:

1. In a photographic printing machine, the combination with a light chamber having a printing aperture, of a lamp in the chamber, an adjustable support therefor comprising two carriages movable at right angles to each other on the wall of the chamber opposite the aperture in lateral directions 60 relatively to the latter, the lamp being directly mounted on one carriage and the latter on the other carriage, and a common operating member controlling both carriages and accessible from the exterior of the chamber. 70

2. In a photographic printing machine, the combination with a light chamber having a printing aperture, of a lamp in the chamber, an adjustable support therefor 75 comprising two carriages movable at right angles to each other on the wall of the chamber opposite the aperture in lateral directions relatively to the latter, the lamp being directly mounted on one carriage and 80 the latter on the other carriage, and a slideable and rotatable operating member accessible from the exterior of the chamber and connected to operate one carriage by its sliding movement and the other by its rotary 85 movement.

3. In a photographic printing machine, the combination with a light chamber having a printing aperture and provided with a track on the wall opposite to said aperture, 90 of a carriage movable on the track, a shaft projecting through a wall of the chamber and journaled on the carriage to move the latter on the track as the shaft is thrust longitudinally, a second carriage guided to 95 move transversely on the first and provided with a rack, a lamp carried by said last mentioned carriage, and a gear on the shaft cooperating with the rack, the movement of both carriages being in transverse directions 100 relatively to the printing aperture.

FREDERICK W. BARNES.
